UNITED STATES PATENT OFFICE.

SAMUEL A. FORTER, OF BELLEVUE, AND ADOLPH H. MEYER, OF PITTSBURGH, PENNSYLVANIA, ASSIGNORS TO H. L. DIXON COMPANY, OF CARNEGIE, PENNSYLVANIA, A CORPORATION OF PENNSYLVANIA.

LEER.

Application filed June 4, 1921. Serial No. 474,965.

To all whom it may concern:

Be it known that we, SAMUEL A. FORTER and ADOLPH H. MEYER, both citizens of the United States, residing, respectively, at 5 Bellevue and at Pittsburgh, both in Allegheny County, in the State of Pennsylvania, have invented a new and useful Improvement in Leers, of which the following is a full, clear, and exact description, reference being had to the accompanying drawings, in which—

Figure 1 is a longitudinal vertical section, partly broken away, of one form of leer embodying our invention;

15 Figure 2 is a vertical section of a portion of the leer, on a larger scale;

Figure 3 is a detail view of one of the pusher rod supporting devices;

20 Figure 4 is a side elevation, partly broken away, looking at the far side of the leer in Figure 1;

Figure 5 is a section on the line V—V of Figure 1;

25 Figure 6 is a detail view showing one pair of the supports for the pusher rods; and

Figures 7 and 8 are detail views showing the connection between the pulling and the pushing rods.

Our invention has relation to glass annealing leers, and more particularly to leers used in the manufacture of plate glass.

Heretofore it has been customary in practice to construct the entrance portion of the leer in the form of a series of zig-zagged 35 communicating ovens through which the glass is moved by alternately pushing it forwardly and laterally. This arrangement has been desirable owing to the fact that no suitable mechanically operated 40 pusher mechanism has been devised which has been capable of effectively feeding entering plates in a direct line through the entrance or oven portion of the leer onto the usual pulling and lifting rods at the cooler 45 portion of the leer, or leer end.

Our invention is designed to provide means of simple and effective character which permits the oven portion of the leer to be arranged in a straight line with the 50 leer end; and also to provide mechanism whereby the glass plates may be pushed directly forward through this portion of the leer onto the usual lifting and pulling rods.

The nature of our invention will be best understood by reference to the accompanying drawings, in which we have shown our invention applied to one form of leer, which will now be described, it being premised, however, that the invention is applicable to other constructions and types of leers, and 55 that the details of construction, arrangement, and combination of the various parts may be widely changed without departing from the spirit and scope of our invention as defined in the appended claims. 60

In these drawings, the numeral 2 designates the oven portion of a glass leer, into which the glass plates A are introduced through an opening 3 on one of the lateral walls of said oven. This oven is arranged 70 in a direct line with the leer end 2^a, so that the plates A, after entering the oven 2, may be moved forward in straight lines throughout the entire length of the leer.

In the drawings, we have illustrated the 75 application of our invention to a leer in which the oven 2 is of the muffle type, this oven having a heating chamber 4 provided with off-take flues 5 leading into a pipe 6 communicating with a stack 7. The particular construction of the leer, however, forms no part of our present invention. 80 8

Figure 5 is a section on the line V—V of Figure 1; Figure 6 is a detail view showing one pair of the supports for the pusher rods; and Figures 7 and 8 are detail views showing the connection between the pulling and the pushing rods.

The cooling portion 2^a of the leer is provided with the usual set of reciprocating pulling rods 9 and with the usual arrangement of vertically movable lifting rods 10, as best shown in Figure 5. The pulling rods 9 are arranged to be reciprocated by the 90 usual cables 11 carried on the drums 12, these drums being actuated by a rack and pinion mechanism 13 (see Fig. 4), actuated in turn by a power cylinder 14. The forward end of the rack member of this rack and pinion device, as it approaches the limit of its forward movement, is designed to contact with a movable member 15, which is seated against an adjustable spring 16, this device being for a purpose which will presently be explained.

The lifting rods 10 are arranged to be operated by any usual mechanism, such as the system of connected levers 17 shown in Figure 4, actuated by a power cylinder 18. 105

This connection may comprise the usual

arrangement of a composite beam 47 extending transversely of the leer below the rods 10 and supporting each of the rods. Each of the levers 17 may be connected at its lower end to a pulley 48 whereby the pulley is rotated upon oscillation of the lever. Each of these pulleys in turn is connected through a chain or cable 49 to the composite beam 47 whereby the beam is raised and lowered in unison with its corresponding lever 17. As these levers are in turn connected for simultaneous movement, it will be apparent that all of the beams 47 are simultaneously raised and lowered, thereby simultaneously raising and lowering all portions of the lifting rods 10. The pulleys 48 and the chains or cables 49 may be mounted in suitable boxes 50 formed in the walls of the leer at the proper points, as clearly shown in Figures 4 and 5.

For the purpose of pushing the glass plates A through the portion 2 of the leer and onto the leer rods, we provide the two longitudinal rods 19 extending longitudinally through said chamber above its floor 20. These rods may be either solid rods, or they may be conveniently formed of length of piping or tubing. Each rod is supported at intervals upon a wheel or roller 21 mounted in a lower portion of a carrier 22, which in turn is supported for limited longitudinal movement on the tracks 23 of a boxlike hanger device 24. A number of these hangers are provided in longitudinal series for each of the rods 19. Each of these hanger devices is shown as supported by means of the two vertical rods 25 (see Fig. 2), which extend upwardly through suitable guides and are connected at their upper ends by a bar or yoke 26 having an upward projection 27 to which is pivotally connected one arm of a lever 28. The lever 28 is actuated by a suitable system of link and lever connections 29, 30, 31, and 32, with one of the levers 17 which actuate the lifting rods of the leer, these connections being best shown in Figure 4. Each of the levers 28 has an upwardly extending arm 33, these arms being connected, as shown in dotted lines in Figure 1, to a common connecting bar 34 for all of the hangers at that side of the leer. The connections just described provide means whereby at the proper times the rods 19 may be lifted vertically a short distance by a simultaneous vertical movement of the hangers 24.

The rods 19 are given an endwise reciprocating movement by being connected to the outside reciprocating pulling bars 9 of the leer, this connection being indicated at 35 in Figure 1 and shown more in detail in Figures 7 and 8. It consists of a transverse bar or bridge member 35^a which connects the two outside pulling bars, and is

provided with two sockets 35^b; and a cross-tie connection 35^c between the two rods 19, having two depending pins 35^d which engage the sockets 35^b and are capable of a sufficient vertical movement therein to permit of an independent vertical movement of the pulling rods, as hereinafter described.

Each rod 19 has secured thereto a plurality of spaced-apart hangers 36 to which the pushing members for the glass are fastened. 75 Each of these pushing members is shown as comprising an angle 37 which extends transversely across the chamber 2 between the two opposite hangers 36 on respective rods 19. The lower horizontal flange of 80 this angle is beveled, as shown at 38 (Fig. 2), so as to pass under the edge portion of the glass plate. Secured to the angle 37 is a pushing member 39, which preferably consists of a strip of some suitable material, 85 such as asbestos, which is designed for direct contact with the edge of the plate to be pushed.

The operation is as follows. During each forward movement of the pulling rods 9 and 90 pusher rods 19, the plates are advanced through the leer a distance substantially equal to their length. At the end of each of these forward movements the forward end of the rack member of the rack and pinion device 13 has engaged the member 15, thereby compressing the spring 16. The compression of this spring at the time the rods 9 and 19 have fully completed their forward movement, is sufficient to exert a 100 short back kick upon the rods 9 and 19. This kick is sufficient to disengage the beveled edge portions or toes 38 of the angles 37 from beneath the glass plates. At this time, the connections already described 105 will operate to simultaneously raise all of the hangers 24, thereby elevating the pusher rods 19 sufficiently to permit the pushers carried by these rods to move backwardly over the glass plates in the leer, into positions to respectively engage the succeeding plates for a new forward movement. The fact that the carriages 22 are capable of a limited longitudinal movement in the hangers 24, enables the rods 19 to make a full return movement of a length somewhat greater than the distance between adjacent pushers; since one of the pushers on its return movement contacts with the carriage 22, it can move said carriage backwardly on its hanger 110 to the necessary extent. This excess movement is necessary owing to the fact that each pusher must move back a distance slightly greater than the length of a glass plate.

The operations above described are repeated in succession, thus causing a gradual advance of each plate A through the leer.

The advantages of our invention will be apparent to those familiar with plate glass annealing leers and with the pushing or 130

stowing operations which have heretofore been necessary in connection with the zig-zag leer chambers commonly employed. Our invention provides a very simple pushing mechanism, operated through connections with the usual leer rod operating mechanisms, for feeding the plates in a straight line through the entrance portion of the leer onto the leer rods. This feeding of the plates is accomplished in a manner which does not injure the glass and which greatly reduces the amount of labor required. The straight line arrangement of the leer greatly simplifies its construction and accomplishes an object which has long been sought in this art.

We claim:

1. The combination with a plate glass annealing leer having longitudinally reciprocable pulling rods and vertically movable lifting rods, of mechanism for feeding the glass plates onto said rods, said mechanism comprising longitudinally extending pusher rods operatively connected to said pulling rods to reciprocate therewith and having depending pushing devices, together with means for automatically raising said pushing rods in unison with the lifting rods to permit the return movements thereof, substantially as described.

2. The combination with a plate glass annealing leer having a continuous straight line oven portion and leer end portion and provided with the usual lifting and pulling rods, of pushing mechanism for feeding the plates through the oven portion onto said rods, and actuating connections between said pushing mechanism and the leer rod mechanism, substantially as described.

3. In a plate glass annealing leer, the combination with the usual lifting and pulling rods, of mechanism for moving the glass plates in a straight line onto said rods, said mechanism comprising pushing members carrying pushers, means to reciprocate said pushing members in unison with the pulling rods of the leer, and connections with said lifting rods to lift said members during their return movements, substantially as described.

4. In a plate glass leer, conveying mechanism comprising longitudinally reciprocable pushing members having transversely arranged pushers, hangers supporting said members, pulling rods co-operating therewith, means for reciprocating said members and said rods, and means for lifting the hangers and thereby said members during the return movements of said members, substantially as described.

5. In a plate glass annealing leer, conveying mechanism comprising longitudinally reciprocable pushing members, a plurality of hangers supporting said members, pulling rods co-operating therewith, means for re-

ciprocating said members, and said rods in unison, and means for lifting said hangers and thereby the members during their return movements, substantially as described.

6. In a plate glass leer having mechanism comprising longitudinally movable pushing members, means for reciprocating said members, a plurality of carriages upon which each of said members is longitudinally movable, a hanger for each of said carriages relatively movable longitudinally thereof, and means for raising the hangers and thereby the carriages and said members, substantially as described.

7. Conveying mechanism for plate glass leers, comprising longitudinally extending pusher rods, longitudinally extending pulling rods, means for reciprocating said rods in unison, means for lifting the rods during their return movements, and depending pushers carried by said rods and extending transversely between them, each of said pushers comprising a beveled member adapted to engage underneath the edge of a glass plate, and a pushing member for engagement with the transverse rear edge of a glass plate, substantially as described.

8. Conveying mechanism for plate glass leers having an oven portion, comprising a plurality of rods extending longitudinally within the oven portion of the leer chamber, a plurality of transversely extending pushers carried by said rods and adapted to engage underneath the rear edge portions of the glass plates and also to engage the rear edge portions of said plates, means for reciprocating said rods, means for lifting said rods during the return movements thereof, and means controlled by said first-mentioned means for causing the disengagement of the pushers from the plates before the rods are lifted, substantially as described.

9. A plate glass leer having an oven portion and a leer end portion arranged in a straight line, lifting and pulling rods in the leer end portion of the leer, and mechanical means operable in timed relation to the operation of said rods for moving the glass through the oven portion of the leer and onto said rods, substantially as described.

10. A plate glass annealing leer having an oven portion and a leer end portion arranged in a straight line, a mechanical pusher for pushing the glass plates through the oven portion and into the leer end portion, and means in the leer end portion for moving the plates therethrough in timed relation to the movement of the plates through the oven portion, substantially as described.

11. A plate glass annealing leer having an oven portion and a leer end portion, the latter having reciprocable pulling rods, a mechanical pusher for conveying the glass plates through the oven portion of the leer,

and connections actuated by the pulling rods for operating the pushing device, substantially as described.

12. A plate glass annealing leer having an oven portion and a leer end portion arranged in a straight line, the leer end portion having longitudinally reciprocable pushing rods and vertically movable lifting rods, and a mechanical pushing device for moving the glass plates through the oven portion onto said rods, connections between said device and the pulling rods for imparting a longitudinal movement to said device, and connections operated by the lifting rods for imparting a vertical movement to the pushing device, substantially as described.

13. In a plate glass leer, conveying mechanism comprising longitudinally reciprocable pushing members having transversely arranged pushers, hangers supporting said members, pulling rods co-operating with said pushing members, means for simultaneously reciprocating said members and said rods, lifting rods, and means for simulta-

neously lifting said hangers and said lifting rods, substantially as described.

14. In a plate glass annealing leer, conveying mechanism comprising longitudinally reciprocable pushing members, pulling rods co-operating therewith, means for simultaneously reciprocating said members and said pulling rods, lifting rods, and means for simultaneously lifting said members and said lifting rods, substantially as described.

15. In a plate glass annealing leer, conveying mechanism comprising longitudinally reciprocable pushing members, pulling rods co-operating therewith, means for simultaneously reciprocating said members and said rods, and means for lifting said members during their return movements, substantially as described.

In testimony whereof, we have hereunto set our hands.

SAMUEL A. FORTER.
ADOLPH H. MEYER.
